UNITED STATES PATENT OFFICE.

FITZ EDWARD PARKLER, OF CHICAGO HEIGHTS, ILLINOIS.

VAGINAL SYRINGE.

Application filed October 18, 1926. Serial No. 142,279.

My invention has reference to improvements in syringes and more particularly to vaginal syringes.

Heretofore, no satisfactory vaginal syringe has been provided which will thoroughly cleanse the walls of the vagina and it is therefore the object of the present invention to provide a novel and practical construction of syringe by which the walls of the vagina can be thoroughly cleansed and irrigated in combination with novel means to dilate the vagina by water pressure to any desired amount or extent, and to retain such position during the process of cleansing, for purposes hereinafter set forth.

Another object of the invention is to provide a syringe with a novel form of hollow injector tube, said tube having a plurality of discharge slots at its forward end positioned between several radially extending flanges and the whole positioned in such a manner so that when the syringe is in position, the cleansing fluid is discharged at the innermost portion of the vagina, or mouth of the womb in a harmless film like spray, after which one of said slots will serve as an unobstructed air passageway between the forward end of the hollow injected tube and the outwardly formed drain channel for purposes hereinafter explained.

Another object of the invention is to provide a syringe of novel construction which will when in position, harmonize perfectly with nature's forces, whereby a woman may be relaxed flat upon her back during the process of cleansing and the entire remaining fluid will be drained from the vagina. Heretofore, it has been difficult to drain the vagina and no practical means has been provided for thoroughly doing this, with the result that the cleansing fluid has to a certain amount, been left in the vagina after the syringing operation. In accordance with the present invention, the earth's force of gravitation as it is exerted upon the air, water and human body is fully reckoned with.

Another object of the invention is to provide a novel valve control for the drain or discharge of the cleansing fluid after carrying on its work in the cleansing operation.

Other and further objects will appear as the description proceeds.

In the accompanying drawings:

Figure 1 is a sectional elevation showing my novel vaginal syringe in position as when

in use during the dilating and draining action of the cleansing and irrigating process.

Figure 2 is an enlarged fragmentary longitudinal sectional view of the nozzle of the 60 syringe.

Figure 3 is a front elevation of the device shown in Figure 2 at the nozzle end thereof.

Figure 4 is a cross sectional view taken on 65 line 4—4 of Figure 2.

Figure 5 is a cross sectional view taken on the line 5—5 of Figure 1.

Figure 6 is a perspective view showing the 70 spray sheets discharged by the nozzle.

Figure 7 is a sectional elevation showing the same nozzle construction with a modified form of controlling valve and bulb connected to the device with a regulating valve of novel construction thereon, and

Figure 8 is a sectional view taken on the line 8—8 of Figure 7.

Referring to the drawings in detail, in which like reference characters designate corresponding parts throughout the several views, and referring to Figures 1 to 6 inclusive as well as the form of nozzle shown in Figure 7, the device comprises an elongated injection tube 1 which is provided at its forward end with a plurality of radially extending tapered flanges 2 which give a star shaped appearance at the forward end of the tube.

These flanges start from the point 3 on the body of the tube externally at the sides and top and nearer the forward end than the rear end and are preferably four in number, although any other number may be provided, and gradually increase in depth or radial dimension and extension from the periphery of the tube through the sloping walls 4 and then extend parallel to the external surface of the tube and axis thereof to the forward end, at which points they are provided with curved edges 5 of convex formation curving inwardly toward the tip of the nozzle and tapering as shown at 6 so as to form a relatively central concavity or recess at the point 7. Between these flanges are positioned a plurality of radial slots 8 of elongated formation extending back slightly into the body of the tube and having forwardly diverging inclined or slanting walls 9 at the rear ends thereof so as to discharge the water or cleansing fluid outwardly and forwardly in radial spray like sheets which prevent injury to the parts treated within the vagina and at the mouth

of the womb. The radially extending flanges are so positioned in relation to the injector tube that when the syringe is in position, the outward surfaces of the two bottom flanges rest upon the same horizontal plane. Formed along the bottom of the tube externally of its wall are a pair of depending or downwardly extending parallel flanges 10 which are relatively wide and 5 tapered at their forward ends as indicated at 11 in a corresponding manner as the flanges 2, between which one of the slots 8 is medially positioned to discharge between the forward ends of the flanges 10. These flanges 15 extend downwardly and rearwardly from the tip of the nozzle at the bottom, the entire length of the injector tube, thus forming with the wall of the tube 1, the top and side walls of a channel 11 which is relatively narrow and deep in construction, being considerably deeper than wide and the inner top wall of the channel may be concaved or 20 the inner portions of the inner faces or surfaces of the flanges 10 may converge inwardly or diverge outwardly so as to slope slightly toward each other to form a concave rounding inner or top wall for the channel while the bottom is freely open the channel as before stated being deeper than wide as 25 specifically designated by the dotted circle in Figure 3 of the drawings. The flanges 10 are also provided with a plurality of spaced parallel and transverse or vertically extending slots 12 which as shown extend part 30 way across the flanges 10 and substantially throughout the length thereof as seen in Figure 1, except at the forward ends which have their edges curved and the flanges tapered gradually upward toward their forward ends and finally terminate at the tip 35 of the injector nozzle near the point 7. At the rear portion of the nozzle, the latter is formed with a substantially annularly shaped flange or collar 13 which extends 40 around the rear end of the tube from the top to the bottom along the sides but terminates on either side by emerging into each rear end of the extended flanges 10 at the bottom, thereby allowing the before mentioned channel 11 to continue to the rear 45 unobstructed. This is due to the fact that the collar 13 is of substantially horseshoe shape or U-shape with the sides tapered downwardly and rearwardly toward the bottom and curved rearwardly and downwardly 50 to a point across the width or depth of the collar as specifically seen in Figure 1 to properly fit the mouth of the vagina.

The injector tube is also extended rearwardly beyond the collar 13 as indicated at 55 14 and externally threaded at its rear end as indicated at 15 forming the inner end of the injector tube so as to support a stopper or shield 16 on the portion 14 in slightly spaced relation to the collar 13 as indicated

at 17 to form a narrow passage way or gap with respect to the adjacent side or face of the collar 13 for the purpose to be herein-after more fully described. The stopper or shield 16 tapers forwardly and at its rear 70 end, is cut out or concaved to form an interior hollow portion 18 to accommodate an internally threaded nipple 19 which engages the threads 15 and abuts up against a shoulder 20 formed at the inner wall of the concavity or hollowed out portion whereby to retain the stopper or shield in position detachably, thereby permitting parts to be readily separated for sterilizing or cleansing, and maintaining the same in an extremely 80 sanitary condition. A supply tube 21 fits over the inner end of the nipple 19, which is beaded as at 20 for this purpose and may extend from a suitable reservoir in the form of a hot water bag, bulb or other means of 85 supplying the cleansing fluid to the nozzle.

The stopper or shield 16 is provided with an outlet or drain passage 22 which is in line with the channel 11 at its forward end, separated only by the narrow passageway 90 17 and slanting downwardly in an inclined position through the shield body while the rear portion thereof extends horizontally and is notched, serrated or threaded internally, as indicated at 23 to take a nipple 24 95 beaded as shown at 25 for engagement by a flexible drain tube 26 adapted to lead to a suitable drain receptacle or waste pipe such as a closet bowl. The nipple 24 is serrated or threaded to engage the portion 23 to secure it in position and has its forward end tapered and provided with slots 27 extending radially while the forward end is concaved to form a seat 28 for a ball or other check valve 29.

This check valve 29 is adapted to close against the seat 28 thereby preventing back flow of the cleansing fluid after it has served its purpose and has drained past the valve, but permitting the discharge or drain 110 thereof through the openings 27 when the ball check valve is unseated as to seat 28 but is against seat or concavity 28 as shown in Figure 1 of the drawings to permit the discharge through the tube or pipe 26 as 115 indicated by the arrow. The induction into the pipe or tube 21 is also indicated by the arrow at the upper extremity thereof supplying the cleansing fluid under a pressure head either natural or forced from a suitable receptacle or bulb.

A regulating or hose clamp is adapted to be positioned over the tubes 21 and 26 in such a manner that both tubes may be compressed simultaneously to stop the flow of 125 liquid through the same, or the drain tube 26 may be closed any desired amount prior to the closing of the inlet or supply tube 21, all of which is accomplished by the manipulation of a single control lever 31 for the 130

purposes and in the manner to be subsequently described. This regulating or hose clamp constituting a shut-off for the flow of fluid consists of a flat body 32 which is arranged beneath the tube 21 in use, preferably consisting of a section of spring or resilient metal with two corrugations formed by a hump or raised part 33 and a depression 34 for the purpose of making better contact with the tube in the shutting off process. On either side of the corrugations is a set of guides 35 and 36, both of annular formation and the former extending upwardly and adapted to receive the tube 21, while the latter extends downwardly and is adapted to receive the drain tube 26 for holding the tubing in place. One end of the body or plate 32 is bent up and turned back in spaced relation to the body as indicated at 37, this end being provided with an opening to likewise receive the tube 21 and this opening centering with the corrugations 34 and 35 and the tube guide 35, the whole of which gives a resilient or spring-like effect to the device.

Near the end of the spring at the top on either side, is provided an offset lug 38 which protrudes through the top holes 39 of lever 31 having enlarged parallel side portions 40 for this purpose and form a pivot axis allowing the lever 31 to swing on a radius of about 180 degrees from that point, dragging with it a U-shaped bail or band 41 which is hung from side portions 40 and disposed to surround the discharge tube 26. The ends of the band 41 are directed or bent inwardly through half round holes 42 in the side portions or jaws 40 of the lever 31, these openings or holes having circular bottom portions and straight top walls all offset from the center lug 38 and apertures 39. The free end of the top portion or spring 43 is provided with a depression or lug 44 opposite or above hump 34 and the lower portion of the plate proper is extended beyond the band or guide 35 as indicated at 45 to provide a finger grip or handle 46 adjacent the rear end of the clamp, with which the user may hold the clamp and syringe securely in position with one hand, thereby allowing her a free hand with which to operate the control lever 31.

The operation of the vaginal syringe will now be described.

The person desiring to use the syringe lies flat upon her back (thereby relaxing all the tension on the muscles) and the injector tube or nozzle 1 inserted into the mouth of the vagina until the stopper or shield 16 completely seals the same, as indicated by dotted lines A in Figure 1. The forward end of the injector tube will then be close to the bottom of the vagina, the wall of which is designated in an inflated position at B in Figure 1, while the mouth of the

womb is designated at C. The hose clamp when in position presses against the rear end of the injector tube by raising the lever 31 and moving it to the dotted line position shown in Figure 1 to close the tube 21 between the corrugations 33, 34 and 44, at which time the ends of the U-shaped bail or band 41 is also drawn against the drain tube 26 to simultaneously close it while the end 44 is pressed down in opposed relation to the part 34, and in this position the straight walls 42 are engaged by the inwardly extending upper ends of the bail or band 41 to retain the device in this position by the spring tension. With the aid of the finger grip or handle 46, the whole is held in position with but one hand. The clamp is opened after the proper supply of cleansing fluid has been provided from a douche receptacle or syringe bulb above, in this case preferably a hot water bottle or other container for the cleansing fluid which is elevated to secure the proper pressure head and the clamp being opened, the tubes 21 and 26 are opened, which allows the cleansing fluid to freely pass through the injector tube 21 and slots 8 thereof to spray the interior of the vagina and walls thereof and at the mouth of the womb in star shaped spray-like sheets shown as X being six in number in the drawing and especially illustrated in Figure 6 assuming a bladed, fan-like or butterfly effect. Due to the tapered thickness near the tip of the side walls of the slots 8, an uneven resistance to the flow of fluid occurs which causes same to alter its course and merge into a star shaped harmless film-like spray which makes contact with the vagina at the innermost point where cleansing begins.

As the fluid continues to be discharged through said slots, it takes an upward course but remains in continuous contact with the walls of the vagina, thereby cleansing entirely where it finally enters the outlet or drain passage 11 formed by the channel or groove 11 due to the latter fitting against the walls of the vagina and partly due to the drain through the slots 12. Owing to the channel 11 being relatively deep and narrow, being deeper than wide, the bottom edges of the flanges 10 are contacted with the walls of the vagina when the latter are not being dilated due to back pressure as shown in Figure 1 of the drawing and as will be subsequently described, thus forming a continuation of the drain channel through the groove beneath the nozzle formed by the flanges 10 across the space 17 at the bottom of the horseshoe shaped collar 13 and out through the drain passage 22 when the valve 29 is unseated, permitting the fluid to escape through the tube outlet 26. The narrow passageway or space 17 is also sealed by the walls of the vagina as clearly indicated at Figure 1 of

the drawing, thus making an unobstructed continuation of the drain passage across this narrow passageway or space, from which it flows into a receptacle on the floor through the flexible drain tube 26. If a thorough cleansing is desired, it may be had by slight manipulation of the clamp control lever 31, which will close the drain tube 26 to any desired amount or degree and permit a 10 faster flow of fluid into the interior of the vagina than the outflow therefrom, owing to the supply tube being open slightly at least, until such time that the accumulated fluid pressure dilates the walls of the vagina 15 as disclosed in Figure 1 of the drawings thereby straightening out all the folds and thoroughly cleansing and sterilizing the same. By holding fast the clamp of the control lever in an upward midway position 20 or other intermediate position as desired according to the degree of dilation which may be required, found necessary or comfortable, the said condition may be continued until a thorough cleansing is assured. It is of 25 course, to be understood that in this dilated condition, all parts of the walls of the vagina and the mouth of the womb may be dilated, thoroughly washed and cleansed and that as soon as the lever 31 is moved 30 back to its original position, this fluid may be discharged through the tube 26 and drained off into a suitable receptacle or waste outlet.

When the supply of cleansing fluid is exhausted, a quantity of said fluid becomes trapped within the interior of the vagina and injector tube due to the fact that the drain passage 22 and the upper portion of the drain tube 26 are on a higher level than 35 the interior of the vagina and the injector tube inserted therein owing to the reclining position of the patient or user. The vagina and injector tube are now emptied of the 40 contents in the following manner: The fluid which fills the drain tube 26 continues its 45 downward course due to its own weight thereby creating a partial vacuum or suction within the walls of the vagina, whereupon the constant air pressure against the 50 outside of the vagina walls, via the body causes it to collapse or flatten beginning at the top and extending downwardly thereby 55 forcing the fluid downward. This escape may be caused partly through the slots 12 in addition to the opening at the front of 60 the channel 11 formed by the flanges 10. At first, the fluid is pushed out through the passageway or space 17 which is highest, and which is open at the top and leads into 65 the space between the channel 11 and the drain passage 22 forcing the fluid into the drain passage 22 and then into the drain tube 26 until the vagina is flattened around the stopper 16 as shown in Figure 1, and 70 downward, whereupon said vagina flattens

across and around the passageway 17 as shown in Figure 1, which is specifically narrow and deep in construction so as to prevent the air pressure from forcing a portion of the soft tissue of the vagina deep into the 70 same whereby it would be rendered useless as a passageway between the drain passage 22 and the channel 11, for purposes hereinafter explained. There is also a constant pressure of air upon said fluid contained in 75 the injector tube via the supply tube 21 from the pressure caused in the receptacle or bulb containing the cleansing fluid. As the draining action continues, the vagina walls collapse around the flange or collar 80 13 and the injector tube 1 and across the bottom edges of the two extended flanges 10 forming the channel 11 thereby closing the bottom of said channel 11 beginning first 85 at the top and then downward as the action continues. As the fluid is forced downward it readily enters the channel 11 at or below the water level at the front end or through openings or slots 12, where it is forced upward through the channel 11 and passageway 17 into the drain passage 22 and finally entering the drain tube 26 past the valve 29 where it discharges into a receptacle that is on the floor. This action continues until 90 the last remaining fluid is forced into the 95 channel 11 and the vagina has entirely collapsed around the drain tube and across the edges of the two extended flanges 10, thereby sealing the channel 11 and the remaining 100 contents therein except for the outlet passage into the passageway 17 at the bottom. The final draining of the channel 11, passageway 17 and drain passage 22 is accommodated as follows: The atmospheric pressure now enters through the supply tube 21 105 and hollow injector tube 1 where it passes into the bottom or the forward end of the channel 11 through the lower discharge slot 8, thereby forcing the remaining fluid upward through the channel 11 and passageway 17 into the drain passage 22 where it 110 passes into the drain tube 26 and drains as before stated. When the action finally ceases and the vacuum is broken, the check valve 29 rolls against its seat 30, thereby 115 preventing a possible backflow of a few drops that may adhere to the drain tube 26.

In practice, I find it essential that the channel 11 must be specifically narrow and deep in construction and especially deeper than wide and substantially so, so as to prevent the air pressure from pressing the soft tissue of the vagina deep into the same whereby it would be rendered useless as a drain passage, the channel in this manner being closed on all sides while the tissues also close the slots 10 or substantially so. It must also extend the entire length of the injector tube with a passageway at the forward end directly between it and the hol- 120 125 130

low injector tube due to the tapered formation of the flanges 10 at the front as indicated at 11'. With this means, a thorough cleansing and draining is provided which 5 heretofore has been impossible.

In addition to the preferred form of syringe above described, I have also provided a modified form, equally as efficient, but of a more compact type, as shown in Figures 7 and 8 of the drawing, in which the construction of the nozzle or injector tube 1 and adjacent parts is the same with the exception of the connections for the tubes 21 and 26 and the controlling means therefor. In this form the nipples 20 and 24 are removed and are replaced with a controlling valve designated generally at 47 in Figures 7 and 8 of the drawings. This valve is of a piston type preferably made entirely of hard rubber and has a casing 48 of cylindrical formation externally threaded at its lower end for receiving an internally threaded enlargement 49 of a nipple 50 having a bead or head 51 over which a tube 52 is fitted, said tube 52 connecting to the bottom of the valve and bearing the regulating and controlling device 32 the same as previously described with exception that the parts 33, 36, 45 and 46 are omitted and the part 35 is left partially open as indicated at 53 and a projection 54 is provided on the plate portions 40. A bulb 55 is also provided on the free end of the tube 52.

The upper end of the casing 48 is internally threaded to receive an aperture plug 56 which is externally threaded for this purpose and provided with air vents or grooves 57 at one or more sides thereof around the stem 58 of a piston 59 which is 35 slidably mounted in the casing 48. This piston is of hollow sleeve-like formation and has its upper end apertured for connection with the stem 58 as by means of the screw or the like 60. The stem 58 also has a pressure button 61 at its upper end for exerting pressure thereon to shift the piston against the action of the spring 62 which is positioned between the apertured upper wall of the piston or screw 60 and a suitable seat 63 in the bottom of the casing at the part 50 around the drain opening 64 thereof. The piston has a slot 65 leading through one side and its lower end is tapered outwardly as shown to direct the fluid through the hollow 55 channel 66 of the piston and through the port or slot 65, which latter is considerably longer than the diameter of either of the passages leading from the valve casing. These passages are indicated at 67 and 70, 60 passage 67 in the upper inlet extension or nipple 68 being internally threaded for engagement with the external threads 15 as indicated at 69 and leading into the injector nozzle or tube 1. The nipple 68 also forms a shoulder to retain the stopper or collar 16 in

position. The lower channel or passageway 70 leads into the drain outlet 22 and has a flange 71 which closes against the outer end of the passageway at its horizontal portion 23 serrated to secure it in position in the 70 manner as heretofore described in connection with the structure shown in Figure 1 of the drawing and containing the ball valve 29 also as previously described. The piston 59 may be made of hard or soft rubber or other 75 material and is held up in place by the coil spring 62 as described, which spring may encircle the valve stem or may be placed inside of the piston and terminating at the nipple 50 as indicated or in any other suitable position. The tube 52 is preferably a short length of rubber tube about 12 inches long over which is placed the single purpose hose clamp described as a modification of the clamp 32 previously referred to. A single 80 ended valved or valveless rubber bulb 55 is secured to the opposite end of the tube and the device is now ready to use.

In the use of this device, the bulb is compressed as much as possible, the slots 8 in 90 the forward end of the tube or injector nozzle submerged into the fluid contained in a suitable receptacle and the bulb released which allows the fluid to be drawn through the injector nozzle or tube 1 and through the 95 slot 65 into the tube 52 and into the bulb which allows the bulb to fill, owing to the bulb being released. The injector tube is now raised and the bulb squeezed until the fluid appears in the slots 8, and when in 100 this position the hose clamp is closed by swinging the lever 31 over in the manner previously described from the intermediate position shown in Figure 7. When in this position, the hose clamp is closed and the 105 syringe may be now placed in position in the vagina in the same manner as shown in Figure 1 of the drawing. The hose clamp is then opened and by squeezing the bulb, it will produce a star spray douche effect, 110 after which the user releases the bulb and with the free hand presses downward on the press button 61 which carries with it the piston 59, moving the slot 65 downward over the passageway 70 and away from the 115 supply passage 67, allowing the air pressure to pass through the air space between the top of the piston 59 around the valve stem and the vents 57 and enter the injector tube. This causes a siphoning action which drains 120 the vagina in the same manner as before stated, the drain being through the passageway 22, passage 70 through slot 65 into the bottom of the casing 48 of the valve 47 and through the nipple 50 into the tube 52 and bulb 55 from which it may be discharged 125 and the parts cleansed in any suitable way.

While I have described my invention in a preferred form, it is also to be understood that various modifications, and changes in 130

the form, arrangement and construction as well as the proportions of the parts may be made without departing from the spirit and scope of the invention.

5 Having thus described my invention, what I claim is:

1. A round hollow injection tube with two flanges projecting from its periphery throughout its length, the walls of the 10 flanges being parallel to each other and so positioned as to bring the two bottom edges of said flanges to rest upon the same horizontal plane and the channel formed by the flanges being much deeper than it is wide, 15 and a plurality of radially extending flanges formed at the forward end upon the exterior surface thereof and gradually tapered toward the tube at their rear ends.

2. A round hollow injection tube having 20 spaced bottom flanges whose walls are parallel to each other and with the two said bottom flanges formed so as to rest upon the same horizontal plane, said flanges extending downward and depending rearwardly 25 from the forward tip end the entire length of the injection tube, thereby completing the top and side walls of a channel specifically narrower than deep in construction and extending from the tip end rearwardly the entire length of said tube.

3. An injection tube and nozzle as specified in claim 2 and having an outwardly formed circular flange on the rear of injection tube, of horseshoe design, the ends 35 of which terminate on either side by merging with each of the aforesaid extending flanges.

4. A vaginal syringe including an injection tube and nozzle as set forth in claim 40 2 and having a circular gap or passage way specifically narrower and deep in construction which separates the aforesaid circular flange and the forward end of stopper or shield.

5. A syringe comprising a nozzle having discharge slots in the tip, and flanges entirely along its length at the bottom forming a narrow drain of less width than its depth, at least one slot positioned between the flanges, 50 and the latter engaged by the walls of the vagina to close the drain except at the tip, said syringe being adapted to siphon fluid from the the vagina and the walls of the vagina cooperating with flanges to form an unobstructed passage way from the exterior to the inner portion of the vagina and return therefrom in conjunction with the nozzle.

6. A vaginal syringe, a hollow injection 60 tube having a plurality of radially extending flanges at the nozzle, said nozzle having a plurality of narrow discharge slots formed between said flanges to discharge the fluid in spray sheets, the bottom of the syringe having a grooved drain projecting therefrom at

its periphery and of uniform width throughout its depth on the exterior of the injection tube and throughout the length thereof, said grooved drain being deeper than wide, and having slots in the flanges thereof, and means for conducting a cleansing fluid through said tube.

7. A vaginal syringe, a hollow injection tube having a plurality of radially extending flanges at the nozzle, said nozzle having a plurality of narrow discharge slots formed between said flanges to discharge the fluid in spray sheets, the bottom of the syringe having a grooved drain projecting therefrom at its periphery and of uniform width 75 throughout its depth on the exterior of the injection tube and throughout the length thereof, said grooved drain being deeper than wide, and having slots in the flanges thereof, and means for conducting a cleansing fluid through said tube, said means having a valved outlet adapted to be closed during the supply of the cleansing fluid and to be opened during the draining action when supply is cut off.

8. A vaginal syringe, a hollow injection tube having a plurality of radially extending flanges at the nozzle end thereof extending around to the tip of the nozzle, said flanges tapering rearwardly and gradually 95 toward the exterior wall of the tube and having their forward ends tapered forwardly and curved inwardly toward the tip of the nozzle to provide a concavity thereat, said nozzle having a plurality of narrow 100 discharge slots formed between said flanges to discharge the fluid in spray sheets, the bottom of the syringe having a plurality of parallel flanges forming a groove externally of its periphery, said flanges having spaced 105 parallel transverse slots substantially throughout its length.

9. In a syringe, a nozzle having a tube with a pair of spaced bottom flanges uniformly spaced apertured apart throughout 110 their width and forming a channel relatively deep and narrow, the forward end of the nozzle having radial slots extending back into the body thereof and flanges between said slots.

10. In a syringe a nozzle having a tube with a pair of spaced bottom flanges with slots and being uniformly spaced apart throughout their width and forming a channel relatively deep and narrow, the forward 120 end of the nozzle having radial slots extending back into the body thereof and flanges between said slots, said flanges being tapered at their forward ends and curved inwardly to form a concavity at the tip of the nozzle.

11. In a syringe a nozzle having a tube with a pair of spaced bottom flanges with spaced transverse slots and being uniformly spaced apart throughout their width and forming a channel relatively deep and nar-

- row, the forward end of the nozzle having radial slots extending back into the body thereof and flanges between said slots, said flanges being tapered at their forward ends 5 and curved inwardly to form a concavity at the tip of the nozzle, and having their rear ends tapered toward the external surface of the body of the nozzle.
12. In a syringe a nozzle having a tube with a pair of spaced bottom flanges uniformly spaced apart throughout their width and forming a channel relatively deep and narrow, the forward end of the nozzle having radial slots extending back into the body thereof and flanges between said slots, a 15 horseshoe shaped collar formed on the rear portion of said tube at the rear ends of the flanges and forming a passageway there-through, a shield on the rear end of the tube 20 in spaced relation to the collar and having a supply passage and a drain passage there-through.
13. In a syringe a nozzle having a tube with a pair of spaced flanges uniformly spaced slotted apart throughout their width and forming a channel relatively deep and narrow, the forward end of the nozzle having radial slots extending back into the body thereof and flanges between said slots, a 25 horseshoe shaped collar formed on the rear portion of said tube at the rear ends of the flanges and forming a passageway there-through, a shield on the rear end of the tube in spaced relation to the collar and having 30 a supply passage and a drain passage there-through, said drain passage extending at an angle from the supply passage and valved means for conducting and draining fluid to and from said passages respectively.
14. In a syringe a nozzle having a tube with a pair of spaced flanges uniformly spaced apart throughout their width and forming a channel relatively deep and narrow, the forward end of the nozzle having radial slots extending and bevelled back into the body thereof and flanges between said slots, a horseshoe shaped collar formed on the rear portion of said tube at the rear ends of the flanges and forming a passageway 45 there-through, a shield on the rear end of the tube in spaced relation to the collar and having a supply passage and a drain passage therethrough, said drain passage extending at an angle from the supply passage, and a 50 valve in the drain passage closed during the supplying of the fluid and open during the draining action.
15. In a syringe a nozzle having a tube with a pair of spaced flanges uniformly spaced apart throughout their width and forming a channel relatively deep and narrow, the forward end of the nozzle having radial slots extending back into the body thereof and flanges between said slots, a 55 horseshoe shaped collar formed on the rear portion of said tube at the rear ends of the flanges and forming a passageway there-through, a shield on the rear end of the tube in spaced relation to the collar and having a supply passage and a drain passage therethrough, said drain passage extending at an angle from the supply passage, and a valve in the drain passage closed during the supplying of the fluid and open during the draining action.
16. A vaginal syringe, a hollow injection tube having a plurality of radially extending flanges at the nozzle, said nozzle having a plurality of narrow discharge slots formed between said flanges to discharge the fluid in spray sheets, the bottom of the syringe having a grooved drain with side openings 60 projecting therefrom at its periphery and of uniform width throughout its depth on the exterior of the injection tube and throughout the length thereof, an outwardly flared collar at the opposite ends of the tube, inner end of the grooved drain terminating 65 adjacent said collar and having a discharge opening therethrough, a shield mounted upon said tube in rear of the collar and held in position thereon, means connected to said tube for supplying a cleansing fluid thereto, said shield having an outlet passage for draining the vagina from said drain and terminating in line with said drain, and a drain pipe connected to said outlet, the mouth of the vagina being adapted to fit 70 around the outer portion of the drain groove and across the collar and shield to effect a continuation of the groove through the shield to the outlet.
17. A vaginal syringe, a hollow injection tube having a plurality of radially extending flanges formed at the outer end thereof, a plurality of discharge slots being formed between said flanges, a pair of substantially parallel flanges extending from the bottom of the tube throughout its length and forming a drain groove along the same specifically narrow and deep, an annular flange on the tube at the rear end of the groove, a shield secured on tube in rear of the collar and having a drain opening therethrough curved toward the collar with a space between the shield and collar adapted to be closed around by the walls of the vagina to form a continuation of the drain groove, and said groove being closed by the walls of the vagina across the edges of the flanges, a tube connected to the injection tube for supplying the cleansing fluid thereto, and a tube connected to the drain for draining the 80 vagina.
18. A syringe comprising a hollow injection tube, a plurality of radially extending flanges formed at the outer end thereof, there being discharge slots positioned be- 85

tween said flanges, spaced parallel depending flanges on the tube forming a grooved drain extending throughout the length of said tube adapted to be closed across the 5 outer side thereof by the walls of the vagina, a stopper positioned at the inner end of said tube in spaced relation with said drain groove, the groove across the edges of the flanges and the space between the groove 10 and stopper being adapted to be closed by the walls of the vagina, said stopper being provided with an outlet passage in alignment with said drain groove, means for conducting a cleansing fluid to said tube, means 15 for conducting said fluid from said outlet passage, and means for selectively opening or closing said fluid conducting means.

19. A syringe comprising a hollow injection tube, there being narrow radial discharge slots at the outer end thereof, a drain groove formed on the outer surface of said tube comprising a pair of spaced walls, extending the whole length of said tube, and disposed in angular relation less than an 25 obtuse angle, a stopper positioned at the inner end of said tube in spaced relation with said drain groove, said stopper being provided with a discharge passage, separate means for conducting the cleansing fluid to 30 and from said tube, means for regulating the flow of said fluid, and means for effecting a siphoning action in the groove and in the vagina when the supply of cleansing fluid has been exhausted.

35 20. A syringe comprising a hollow injection tube, a plurality of radially extending flanges formed at the outer end thereof, discharge slots being positioned between said flanges, flanges extending from the periphery 40 of the tube throughout the length thereof at the bottom and forming a drain groove throughout the length of the tube, said groove being deeper than it is wide, and means to conduct and drain a cleansing fluid 45 to and from the nozzle and drain groove respectively.

21. A syringe comprising a hollow injection tube, a plurality of radially extending imperforate flanges formed at the 50 outer end thereof, discharge slots being positioned between said flanges, perforated flanges extending from the periphery of the tube throughout the length thereof at the bottom and forming a drain groove throughout 55 the length of the tube, said groove being deeper than it is wide, and means to conduct and drain a cleansing fluid to and from the nozzle and drain groove respectively.

22. A syringe comprising a hollow injection tube, a plurality of radially extending flanges formed at the outer end thereof, discharge slots being positioned between said flanges, flanges extending from the periphery 60 of the tube throughout the length thereof at the bottom and forming a drain groove 65

throughout the length of the tube, said groove being deeper than it is wide, a stopper positioned at the inner end of said tube in spaced relation with said drain groove, said stopper being provided with an outlet passage in 70 alignment with said drain groove, means for conducting a cleansing fluid through said tube, means for conducting said fluid from said outlet passage, and means for selectively opening or closing said fluid conducting means and for simultaneously closing the same whereby to supply the fluid 75 without discharge for dilating the vagina or for creating a siphoning action to discharge all of the cleansing fluid from the so vagina through said groove and portions of the vagina positioned therebeneath.

23. A vaginal syringe comprising a hollow injection tube, discharge slots at the outer end thereof, a grooved channel formed along the bottom of the tube from tip to rear end thereof and having spaced substantially parallel walls forming a relatively deep groove of no greater width than in depth, a collar on the rear end of the tube, 90 a stopper positioned at the inner end of said tube in spaced relation to the collar and drain groove and provided with a discharge passage forming a continuation of the drain groove, said stopper being adapted to fit the vagina whereby the latter will seal the space between the collar and the stopper and also the open side of the tube, separate means for conducting the cleansing fluid to and from said tube, means for regulating the flow of said fluid, said means by a single operation serving to individually open or close said conducting means or to simultaneously close the same, and adapted to affect the siphoning action in the groove when a 95 supply of cleansing fluid has been exhausted from the conducting means whereby to entirely drain the bottom of the vagina.

24. In a vaginal syringe, a round hollow injection tube having spaced parallel walls 100 projecting from one side thereof in the direction of chords of arcs of the circle of the tube and a plurality of radially extended flanges formed at the forward end of the tube upon the exterior surface thereof and 105 provided with slots therebetween.

25. A vaginal syringe including a hollow injection tube having walls parallel to each other and a plurality of radially extending flanges so positioned as to envelope the tip 110 of the tube and forward portion thereof and provided with radial slots therebetween, said flanges gradually tapering in radial dimension toward the tip end of the tube and turned in to form a central concavity.

26. A syringe of the class described, including a tube having a pair of spaced parallel flanges along the bottom extending in the same horizontal plane and forming a narrow drain groove therebetween from the 115 120 125 130

tip to the rear end of the tube, conducting means for conveying fluid to the tube, discharge means at the forward end of the tube around the periphery thereof, and drain 5 means leading from the rear end of the groove.

27. A syringe of the class described, including a tube having a pair of spaced parallel flanges along the bottom extending in 10 the same horizontal plane and forming a narrow drain groove therebetween from the tip to the rear end of the tube, conducting means for conveying fluid to the tube, discharge means at the forward end of the tube 15 around the periphery thereof, drain means leading from the rear end of the groove and means for independently or simultaneously controlling said conducting and draining means, to independently or simultaneously 20 open and close the same.

28. A syringe of the class described, including a hollow injection tube having slotted walls parallel to each other and a plurality of radially extended flanges so positioned as to bring the bottom ones of said flanges to rest upon the same horizontal 25 plane.

29. A syringe of the class described, including a round hollow injection tube hav-

ing a pair of spaced parallel flanges along 30 the bottom thereof parallel to the axis of the tube and with their outer edges in the same horizontal plane, flanges extending from the forward end of the tube to the tip thereof and having radial slots therebetween, said 35 groove extending from the tip end of the injection tube to the rear end thereof, means for conveying fluid through the tube, and means leading from the rear end of the groove to drain the same. 40

30. In a vaginal syringe, a nozzle having discharge slots in its tip and a bottom groove externally throughout its length, a shield on the inner end of the tube and having a drain extension leading to the rear of the groove, 45 a supply tube connected with the nozzle in rear of the shield, a drain tube connected to the extension, and a valved means interposed in the supply tube, including a regulating clamp on the tubes, said clamp having engagement with both tubes and provided with means to simultaneously close the same, to partially close the drain tube prior to closing the supply tube or to leave 50 both tubes freely open. 55

In testimony whereof I affix my signature.

FITZ EDWARD PARKLER.
